UNITED STATES PATENT OFFICE.

WARREN FRASIER, OF PHILADELPHIA, PENNSYLVANIA, ASSIGNOR TO UNITED SHOE MACHINERY COMPANY, OF PATERSON, NEW JERSEY, A CORPORATION OF NEW JERSEY.

LEVELING-MACHINE.

1,203,523.

Specification of Letters Patent. Patented Oct. 31, 1916.

Application filed February 14, 1913. Serial No. 748,344.

To all whom it may concern:

Be it known that I, WARREN FRASIER, a citizen of the United States, residing at Philadelphia, in the county of Philadelphia and State of Pennsylvania, have invented 5 certain new and useful Improvements in Leveling-Machines; and I do hereby declare the following to be a full, clear, and exact description of the invention, such as will 10 enable others skilled in the art to which it appertains to make and use the same.

The present invention relates to leveling machines, and more particularly to that type 15 of machine which comprises a leveling roll and a coöperating shoe supporting jack relatively movable to change the relative longitudinal position of the roll and jack.

The object of the present invention is to provide a machine of the above character 20 which is simple in construction and which is capable of securing uniformly good results upon varying classes of shoes.

With the above object in view, one feature 25 in a machine of the class described having a leveling roll provided with one or more striking faces and a shoe supporting jack, of means interposed between the roll and shoe sole to receive the direct blows of the striking faces as the roll is rotated.

Still further features of the invention consist in certain novel features of construction, combinations and arrangements of parts hereinafter described and claimed, the advantages 35 of which will be obvious to those skilled in the art from the following description.

In the accompanying drawing, a side elevation of a machine embodying the several 40 features of the invention in their preferred form is illustrated.

The machine shown in the illustrated embodiment of the invention is designed more particularly for operation upon the soles 45 of turn shoes and it is considered desirable when leveling these shoes to deliver a series of blows upon the sole of the shoe to beat out the sole and cause it to conform to the curvature of the last. This operation is 50 conveniently performed by a continuously rotated leveling roll provided with a plurality of striking faces which are arranged to deliver a series of rapid blows upon the sole as the shoe supporting jack is moved

under the roll. In the present invention, the 55 beating out operation is satisfactorily performed and the sole is bedded upon the last without marring or otherwise injuring the surface by the provision of a flexible or resilient shield which engages with the sole 60 and which is arranged to receive the direct blows of the striking faces as the roll is rotated. In the simplest and most efficient form of the invention which has yet been devised, this shield consists of a curved metallic band 65 which surrounds the lower portion of the roll and which is interposed between the roll and shoe in such a manner that when the roll is rotated the striking faces successively contact with the lowest portion of the band 70 which engages the shoe.

The machine consists principally of a shoe supporting jack 2 pivoted to the machine frame at 4 and a leveling roll 5 journaled in the outer free end of a roll supporting 75 arm 6 which is pivoted in the upper portion of the machine frame at 7. The roll 5 consists of a plurality of small rolls 8 which are arranged to successively act upon the sole as the roll is revolved and the faces of which 80 constitute the striking faces of the roll 5. A continuous rotation is imparted to the leveling roll in the usual manner from a main drive shaft 10, a drive pulley 11 mounted thereon, and connecting belts 12 and 13. 85 The roll is pressed downwardly upon the shoe sole by a tension spring 16 which is connected to the frame at its lower end by a link 17 and to the roll carrying arm at its upper end by an adjustable connection consisting of a threaded link 18 and hand wheel 19 arranged to adjust the tension of the spring and vary the pressure of the roll upon the work. The downward movement 90 of the roll when the shoe is removed from 95 engagement therewith is limited by a stop rod 20 connected at one end to the frame of the machine and at its opposite end through an adjustable hand wheel 21 with a rearwardly extending portion 22 formed upon 100 the arm 6.

The leveling roll 5 is journaled in a head 25 which is swiveled in the outer end of the roll carrying arm in order that the roll may be tilted laterally and cause the sole to conform to the curvature of the last in cross section. A simple and efficient mechanism 105 under the control of the operator is pro-

vided for securing this lateral inclination which consists of a toothed segment 26 pivoted at 27 upon the supporting arm 6 and meshing with a bevel gear 28 pinned to 5 the inner end of the head 25. The toothed segment 26 is oscillated by a handle 30 extending into a position conveniently accessible to the operator and by manipulating the handle in a vertical direction any desired 10 lateral inclination may be imparted to the roll. As the leveling roll 5 is rotated, the direct blows of the rolls 8 are received upon a metallic band or shield 31 which is supported slightly eccentric to the roll 5 in 15 order that the small rolls 8 shall only contact with the lowest portion of the band which engages the sole. The curved band 31 is preferably formed of resilient sheet metal which is arranged to yield or give slightly 20 when each roll contacts therewith to thus transmit the blows of the leveling roll indirectly to the surface of the sole, causing the sole to be leveled without marring or injuring the surface of the same. In order to 25 vary the force with which these indirect blows are delivered upon the sole, the position of the band relative to the roll may be adjusted, thereby causing the rolls 8 to strike with a greater or less degree of force 30 upon the band as the leveling roll 5 is rotated. The band 31 has one end pivotally secured at 32 to the head 25 and its opposite end is adjusted relative to the head by a stop screw 33 bearing against the upper end 35 of the band. The end of the band is enlarged and provided with a rectangular slot which embraces a square stud 34 secured in the head 25, thus affording provision for a vertical movement of this end of the band 40 relative to the head. It will be noted that when the machine is in operation, the lowest portion of the band 31 engages with the shoe sole and the pressure imparted by the spring 16 causes the band to be forced upwardly 45 with relation to the roll until its movement is limited by the stop screw 33 which positions the band with relation to the leveling roll 5 and consequently determines the force or extent of the blows which are delivered 50 by the small rolls 8 upon the band.

It is a desirable requisite in machines of this character that the shoe supporting jack may be readily adjusted to accommodate varying sizes and styles of shoes, that the 55 shoes may be firmly clamped in position upon the jack, and that when clamped upon the jack they shall always be supported in the same position relative to the leveling roll. The jack 2 consists of a supporting 60 bed or frame 35 pivoted to the frame of the machine at 4 and having the usual heel post 36 and toe post 37 slidably supported thereon. In order to conveniently adjust the positions of the heel and toe posts to accommodate 65 varying sizes of shoes, they are con-

nected together by an adjusting rod 38 having its ends threaded in opposite directions and connected with the posts 36 and 37 to cause the simultaneous movement of the posts toward and from one another as the 70 rod 38 is rotated in either direction. The heel post 36 is of the usual construction having a last pin 40 pivoted thereto at 41 and provided with mechanism for actuating the last pin which comprises a pivoted cam 75 plate 42 engaging with the lower end of a sliding pin 43 which contacts at its upper end with the under side of the last pin 40. In order to secure the same relative position of the shoe and leveling roll independently 80 of the size of shoe, a heel gage 45 is pivotally secured at 46 to the bed 35 of the jack and has an inturned upper end arranged to project over the heel of the shoe, serving to both position and clamp the shoe when the 85 machine is in operation. With this construction, the heel gage is permanently fixed in a vertical position relative to the jack and also to the toe post 37 which has no provision for vertical adjustment. The heel post 90 of the jack is adjusted vertically to move the shoe into engagement with the gage 45 by mounting the post upon a slide 50 which is moved vertically by an operating cam 51 fulcrumed at 52 upon the bed 35 and provided with a handle 53. The operating cam 51 is provided with a curved operating face engaging with the lower end of the slide and designed in such a manner that when the heel of the shoe is forced against the gage 100 45 the cam will retain it in this position until released by the operator. It will be noted that the adjusting rod 38 is journaled in the slide 50 and moves vertically with the slide relative to the toe post 37. The adjusting rod 38 is threaded into a nut 55 which is slidably mounted in dove-tailed ways 56 formed upon the side of the toe post 37, thus causing the toe post to move toward 105 and from the heel post when the rod is rotated, but allowing the rod to be moved vertically relative to the toe post without disturbing the relative positions of the toe and heel posts.

In the present machine, the actuating 115 mechanism is arranged to impart one complete oscillation of the jack back and forth beneath the roll and the machine is then automatically stopped with the roll positioned approximately above the toe of the 120 shoe. After the machine has been stopped, the jack is conveniently disconnected from the actuating mechanism to allow it to be swung out from beneath the roll and facilitate the removal of a finished shoe and the 125 application of a new one. The jack is oscillated by a rotary path cam 60 secured to a shaft 61 and rotated from the main drive shaft through the pulleys 62 and 63 and a connecting belt 64. The jack is oscil- 130

lated from the cam 60 through a connecting rod 65 which is connected to a slide 66 having provision for adjustment to and from the fulcrum of the jack to vary the extent 5 of oscillation imparted to the jack by the actuating cam. The slide 66 is supported in dove-tailed ways 67 formed in the bed 35 and an operating lever 68 is connected thereto to adjust the position of the slide. 10 The slide is retained in any adjusted position by a toothed quadrant 69 which is engaged by a spring pressed latch 70 supported upon the adjusting lever. The drive shaft is actuated by any suitable form of 15 clutch mechanism which is controlled by a shipper rod 75 connected to a forked clutch lever 76 through a bell crank 77. The shipper rod 75 is normally moved to engage the clutch by a spring 78 interposed be- 20 tween a bearing member 79 formed upon the frame of the machine and a collar 80 secured to the shipper rod. The shipper rod is automatically moved at a predetermined time to disengage the clutch by a 25 lever 81 pivoted centrally to the frame at 82 and having its upper and lower ends connected respectively with the cam 60 and engaging with the end of the shipper rod 75. The upper end of the lever 81 is con- 30 veniently connected to the rod 65, thus forming a support for the end of the rod and causing the lever to be oscillated at the proper time to automatically disengage the clutch by the cam 60. In order to start the 35 machine, the end of the shipper rod 75 must be removed from engagement with the lever 81 and to this end a member 85 is hinged to the free end of the shipper rod and is normally positioned in alignment 40 therewith. A treadle rod 86 is journaled in the frame of the machine below the shipper rod and is connected therewith by a crank arm 87 and connecting link 88, thus causing the free end of the member 85 to 45 be swung clear of the lever 81 when the treadle 86 is oscillated. With this construction, it will be noted that the machine may be started by swinging the member 85 out of its normal position and after the machine 50 is started, if the member is then moved back to its initial position the machine will be automatically stopped at the completion of a single cycle, or by allowing the member to remain in its raised position, the machine 55 will operate for an indeterminate length of time, completing any desired number of cycles.

In order to allow the jack to be conveniently disconnected from the actuating 60 mechanism, the rod 65 is provided with a lateral stud 89 which is engaged by a hook 90 supported upon the slide 66. An operating lever 91 is pivoted to the slide above the hook and is connected therewith in any 65 suitable manner to disengage the hook from

the stud 89 and allow the jack to be swung clear of the roll when the machine is at rest. In order to hold the rod 65 in engagement with the hook 90 when the machine is in operation and to prevent the displacement of the rod when the jack is disengaged therefrom, a finger 93 is formed integrally with the slide 66 and contacts with the under side of the rod 65 to support the rod and to normally maintain the stud 89 in engagement with the hook 90. 70

While it is preferred to employ the specific construction and arrangement of parts shown and described, it will be understood that this construction and arrangement is 80 not essential except so far as specified in the claims, and may be changed or modified without departing from the broader features of the invention.

The invention having been described, 85 what is claimed is:—

1. A leveling machine having, in combination, a leveling roll having one or more striking faces, means for continuously rotating the roll, a shoe supporting jack, 90 means for changing the relative longitudinal position of the roll and jack, and means interposed between the roll and the shoe sole to receive the direct blows of the striking faces as the roll is rotated. 95

2. A leveling machine having, in combination, a leveling roll having one or more striking faces, means for continuously rotating the roll, a shoe supporting jack, 100 means for changing the relative longitudinal position of the roll and jack, and a resilient shield bearing upon the shoe and arranged to receive the direct blows of the striking faces as the roll is rotated.

3. A leveling machine having, in combination, a leveling roll, a shoe supporting jack mounted beneath the roll, a rotary cam for moving the jack beneath the roll to change the relative longitudinal position of the roll and jack, connections between the cam and 110 jack including a slide block for adjusting the extent of movement of the jack, and means under the control of the operator supported upon the slide block for disconnecting the jack from the rotary cam. 115

4. A leveling machine having, in combination, a leveling roll, a shoe supporting jack having toe and heel posts, means for changing the relative longitudinal position of the roll and jack, means under the control of the operator for securing a simultaneous adjustment of the toe and heel posts toward and from one another, and means for securing a bodily vertical adjustment of the heel post. 120

5. A leveling machine having, in combination, a leveling roll having a plurality of striking faces, means for continuously rotating the roll, a shoe supporting jack, 130 means for changing the relative longitu-

dinal position of the roll and jack, a resilient curved shield interposed between the roll and the sole of the shoe, and means for adjusting the position of the shield relative to the roll to vary the force of the blows delivered by the roll.

6. A leveling machine, comprising, a leveling roll, a shoe supporting jack, mechanism for relatively actuating the leveling roll and jack, a clutch operating shipper rod, means for normally moving the shipper rod in a direction to engage the clutch, a lever arranged to actuate the shipper rod in the opposite direction, a member pivoted to the shipper rod and forming the connection between the shipper rod and lever, and means under the control of the operator for moving the member to disconnect the shipper rod and lever.

20 7. A leveling machine, comprising, a leveling tool, a shoe supporting jack, a clutch operating shipper rod, a rotary cam, means for oscillating the jack, means for imparting a clutch disengaging movement to the shipper rod, and a single operative connection between the aforesaid means and the rotary cam.

8. A leveling machine comprising a roll supporting arm, a head swiveled in the outer end of the arm, a bevel gear secured to the head, a toothed segment fulcrumed upon the arm and engaging with the bevel gear, and a handle connected to the toothed segment and extending into a position conveniently accessible to the operator to incline the roll relative to the shoe.

9. A leveling machine, having in combination, a leveling roll, a shoe supporting jack, a rotary cam for actuating the jack, a link operatively connecting the cam and jack, a stud secured to the link, a pivoted hook upon the jack arranged to engage with the stud and connect the jack to the link, and an

operating lever for disengaging the hook from the stud.

45

10. A leveling machine, having in combination, a leveling roll, a shoe supporting jack, a slide block supported upon the jack, a rotary cam, a link connected at one end to the cam, a finger projecting from the slide block and arranged to support the opposite end of the link, and detachable connections between the link and slide block.

11. A leveling machine, having in combination, a leveling roll, a shoe supporting jack comprising a toe post and a heel gage positioned at a predetermined height, a heel post, and mechanism for adjusting the heel post vertically to cause the heel seat of the shoe to engage with the heel gage and position the shoe bottom at a predetermined height with relation to the leveling roll.

12. A leveling machine, having in combination, a leveling roll, a shoe supporting jack comprising a toe post and a heel gage positioned at a predetermined height with relation to the leveling roll, a heel post, and a cam member controlled by the operator and arranged to impart a vertical movement to the heel post to bring the heel seat of the shoe into contact with the heel gage and position the shoe bottom at a predetermined height with relation to the leveling roll.

13. A leveling machine, comprising, a leveling tool, a shoe supporting jack, a rotary cam, a clutch operating shipper rod, a jack actuating rod connected at its inner end to the cam, and a lever supporting the inner end of the rod and actuated by the cam to move the shipper rod in a direction to disengage the clutch.
